UNITED STATES PATENT OFFICE.

LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

BLOCK-SIGNAL SYSTEM.

1,091,133.

Specification of Letters Patent. Patented Mar. 24, 1914.

Application filed July 5, 1910. Serial No. 570,260.

To all whom it may concern:

Be it known that I, LAURENCE A. HAWKINS, a citizen of the United States, residing at Schenectady, county of Schenectady, 5 State of New York, have invented certain new and useful Improvements in Block-Signal Systems, of which the following is a specification.

My invention relates to block signal systems and particularly to signal systems operated by alternating current.

In my prior application Serial No. 511,663, filed August 7, 1909, I have disclosed an alternating current block signal system in which the signals are arranged to give the three indications of danger, caution, and clear, and are controlled without line wires by contact for shifting the phase of the alternating current in the track circuit; 10 two relays being provided for each block, each relay being of the type having two co-operating windings, one connected to the track and the second supplied with current independently of the track circuit. The 15 currents in the second windings of the relays of each pair were of different phase, so that one relay was effected by the variation in phase of the track current while the other remained unaffected thereby. One of these 20 relays controlled the caution and the other the clear indication of the signals.

In the system of my prior application all the signals and relays were placed at the entrance of the blocks. When the blocks the long many signal engineers prefer to give the caution indication by a distant signal placed at an intermediate point in the block for the reason that if the caution indication is given at the entrance of a long block, so that it is not necessary for a long train to slacken its speed immediately, the engineer may forget that he has received the caution indication and approach the next signal at too high a speed to stop if that 45 signal is at danger.

The object of my present invention is to provide a modification of my former application adapted for the control of signals when the distant signal is placed at an intermediate point in the block.

The novel features which constitute my present modification will be specifically pointed out in the appended claims.

For a better understanding of my inven-

tion reference may be had to the accompanying drawings, in which—

Figure 1 shows diagrammatically a block signal system arranged in accordance with my invention, and Fig. 2 shows a modification thereof.

In Fig. 1, A represents the track rails which are separated at the ends of the blocks in the usual manner by insulated joints a. B, B' and B² represent home signals at the entrance of the blocks. B³ and B⁴ represent distant signals at intermediate points in the blocks. C represents a three-phase transmission system through which the alternating current is supplied for the signal system. D, D' and D² represent transformers at the home signals. These transformers are arranged with the well-known three-phase, two-phase connection, so that two-phase voltages are delivered by their secondary windings. D³ and D⁴ are single-phase transformers at the distant signals. E, E' and E² represent track transformers, the primaries of which are connected to the secondaries of the transformers D, D' and D², through contacts b, b', and b² actuated by the signals B, B', B² respectively. The secondaries of these transformers are connected to the track rails and supply alternating current thereto. The purpose of the contacts b, b' and b² is to shift the 75 connections of the primaries of the track 80 transformers from one phase to the other of the transformers D, D' and D² and thereby to shift the phase of the track current, in the manner disclosed in my prior application. e e represent impedances in series 85 with the primaries of the track transformers. These impedances serve the double purpose of preventing an excessive current from flowing when the secondaries of the track 90 transformers are short-circuited by trains, and of permitting the primary of the track transformer to be connected to the second phase of the line transformers before the connection to the first phase is broken. 95 Thus the relays are not even momentarily deenergized when the connections of the track transformers are changed. F, F' and F² represent track relays at the entrances 100 of the blocks controlling the home signals B, B' and B², respectively. F³ and F⁴ are track relays located at the distant signals 105 and directly controlling these signals. Each

of the track relays is shown diagrammatically as of the well-known induction type comprising a short-circuited secondary member f carrying the relay contacts, a winding 5 f' connected to the track rails, and a second winding f^2 supplied with current independently of the track rails from the transformers D , D' and D^2 . The winding f' of relays F^3 and F^4 is connected across an insulated 10 joint a' inserted in the track rail. The same winding of relays F , F' and F^2 is connected across the track rails in the usual manner. The track windings of relays F^3 and F^4 are thus inserted in the track circuit 15 between the transformer and the relay at the end of the track circuit controlling the home signal. Beneath each relay is placed a vector diagram indicating the electrical conditions in the windings of the relay. Relay F is short-circuited by a train, indicated at G , so that its track winding f' is deenergized, the relay contacts are open, and the signal B is at stop position. The winding f' is energized as is indicated in the 20 vector diagram below this relay, $o-if^2$ indicating the voltage impressed on this winding and $o-if'$ representing the current lagging nearly 90 degrees behind this voltage because this winding is highly inductive. 25 Since the coöperation of both windings is necessary to give the relay a torque, the energization of winding f^2 alone has no effect upon the relay. With signal B at stop position, the contact b connects the primary of 30 track transformer E across the right-hand secondary of the polyphase transformer D . This is the same phase as that to which winding f^2 of relay F is connected but the track circuit has a much higher power factor 35 than the winding f^2 , so that the current in the secondary of transformer E may be represented by $o-if'$ in the vector diagram immediately below relay F^3 . This is the current in the winding f' of this relay. The 40 winding f^2 of this relay is connected to the secondary of the transformer D^2 which impresses upon it a voltage displaced 90° from the voltage impressed on the corresponding winding of relay F . The voltage and current in winding f^2 of relay F^3 may, consequently, be represented by $o-vf^2$ and $o-if^2$, 45 respectively, in the diagram below the relay. The currents in the two windings of this relay, consequently, are displaced by approximately 45 degrees. If the relay is so arranged that it has a torque in the direction for closing its contacts when the current in the track winding leads the current in the other winding, then with the relative current phases existing in relay F^2 the relay 50 will have a reverse torque and its contacts will be held open both by its reverse torque and by gravity. In relay F' the current in the track winding f' is the same as in the 55 corresponding winding of relay F^3 and is,

therefore, as indicated by $o-if'$ in the vector diagram below relay F' . The second winding f^2 of this relay is connected the same as the corresponding winding of relay F , so that its voltage and current may be represented by $o-vf^2$ and $o-if^2$ respectively. Under these conditions the current in the track winding of the relay leads the current in the other winding by about 45 degrees, so that the relay is energized with a torque which closes its contacts and signal B' is cleared. With signal B' in clear position, contact b' connects the primary of transformer E' to the left-hand secondary of transformer D' . The voltage in the track circuit in which transformer E' is connected is, therefore, 90° displaced from that in the track circuit next in advance. The current in winding f' of both relays F^4 and F^2 may, therefore, be represented by $o-if'$ in the 70 diagrams beneath these relays, $o-if'$ in these diagrams being displaced 90° from $o-if'$ in the diagrams below relays F^3 and F' . The conditions in the windings f^2 of relays F^4 and F^2 are precisely the same as in the corresponding winding of relays F^3 and F' . It will be seen from the diagrams that the track current leads the current in the other windings by approximately 45 degrees in relay F^4 and approximately 135 degrees in relay F^2 . Both of these relays, are, consequently, energized and both distant signal B^2 and home signal B^3 are cleared. 80 With the arrangement shown only two relays are required for the control of the signals and no line wires, except the transmission lines, are required. With very long blocks, or when the ballast is poor, so that the track leakage is high, it may be desirable to employ two track circuits per block. 85 In such a case the arrangement shown in Fig. 2 may be employed. In this arrangement one track circuit extends from home signal B to distant signal B^2 and the other from distant signal B^2 to home signal B' , 90 the two track circuits constituting a single block. In this case it is necessary to provide an additional relay since a relay for controlling the home signal must be included in the track circuit between signals B and B^2 . 95 This relay may control the connections of the track circuit between signals B^2 and B' , so as to control the relay at the signal B' . The connections of the windings of relays F , F^2 and F' are precisely the same as in Fig. 1, so that the vector diagrams for these relays are the same as in Fig. 1. Relay F' controls through its contacts the circuit of track transformer E^2 . When the relay F' is short-circuited by a train its contacts are 105 open and the primary circuit of transformer E^2 is broken, so that the track circuit of relay F^3 is deenergized. Thus relay F^3 is deenergized by a train at any point between signals B' and B . In order to give relay 110

F^3 the maximum torque, the connections between the two secondaries of transformer D^2 and the primary of transformer E^2 may be arranged as shown so that the voltage impressed on the primary of transformer E^2 is the resultant of the two secondary voltages of transformer D^2 . With this connection the current in winding f' of relay F^3 will be as represented by $o-if'$ in the diagram below it, that is, 45 degrees from the track current $o-if'$ in the track windings of relays F^2 and F' . If winding f^2 is connected as shown, the currents in the two windings of relay F^3 will be displaced from each other approximately 90 degrees, as shown in the vector diagram below this relay and will thus give the maximum torque. The operation of this modification will be obvious from the drawing and from the description which has already been given in Fig. 1.

I do not desire to limit myself to the particular connecting and arrangements of parts shown, but aim in the appended claims to cover all modifications which come within the spirit and scope of my invention.

What I claim as new and desire to secure by Letters Patent of the United States is:—

1. In a block signaling system, home signals at the entrances to the blocks, distant signals at intermediate points in the blocks, track circuits for the blocks, means controlled by the presence and absence of a train in a block for supplying one phase or another of current to the track circuit in the rear of said block, track relays directly controlling the distant signals and track relays controlling the home signals, each track relay having two windings coöperating to close the relay contacts, one of which windings is connected with the track rails, means

for supplying the second winding of each distant signal relay with current of a phase which will coöperate with one only of the phases in the track rails to close the relay, and means for supplying the second winding of each home signal relay with current of a phase which will coöperate with either phase in the track rails to close the relay.

2. In a block signaling system, home signals at the entrances to the blocks, distant signals at intermediate points in the blocks, track circuits for the blocks, means controlled by the presence and absence of a train in a block for supplying one phase or another of current to the track circuit in the rear of said block, track relays directly controlling the distant signals and track relays controlling the home signals, each track relay having two windings coöperating to close the relay contacts, an insulated joint inserted in a track rail of each block, one winding of each distant signal relay being connected across the adjacent insulated joint and one winding of each home signal relay being connected across the track rails, means for supplying the second winding of each distant signal relay with current of a phase which will coöperate with one only of the phases in the track rails to close the relay, and means for supplying the second winding of each home signal relay with current of a phase which will coöperate with either phase in the track rails to close the relay.

In witness whereof, I have hereunto set my hand this 2nd day of July, 1910.

LAURENCE A. HAWKINS.
